UNITED STATES PATENT OFFICE.

EMIL A. LEHMANN, OF NEW YORK, N. Y.

SHIRT.

SPECIFICATION forming part of Letters Patent No. 357,325, dated February 8, 1887.

Application filed March 9, 1886. Serial No. 194,574. (No model.)

To all whom it may concern:

Be it known that I, EMIL A. LEHMANN, of the city, county, and State of New York, have invented certain new and useful Improvements 5 in Shirts, of which the following is a specification.

The attaching of shirt-cuffs to the wrist-studs of shirts is generally connected with some difficulty, owing to the stiffening imparted to 10 the cuffs by the starching and ironing. Various devices have been proposed to facilitate the connection of the cuffs with the sleeves, which are, however, objectionable as they are detachable and do not form a part of the shirt 15 itself.

The object of this invention is to furnish a shirt with a cuff-holding device, by which not only the attaching and detaching of the cuffs are greatly facilitated, but also the position of 20 the cuffs on the sleeves readily adjusted as required by the length of sleeve or size of the cuff, so that the cuffs do not unnecessarily protrude beyond the coat-sleeves.

The invention consists of a shirt, the sleeves 25 of which are provided, in line with the wrist-opening, with a tab, having one or more button-holes, that is attached to a stud of the cuff or to a button back of the wrist-opening of the sleeve when it is desired not to use the cuff- 30 holding tab.

In the accompanying drawings, Figure 1 represents a side elevation of a shirt-sleeve with my improved cuff-holding tab. Fig. 2 is also a side view showing the cuff adjusted 35 higher up on the sleeve than in Fig. 1. Fig. 3 is a vertical longitudinal section on line $x-x$, Fig. 2.

Similar letters of reference indicate corresponding parts.

40 In the drawings, A represents the sleeve of a shirt, to the wrist-opening of which is applied a tab, B, having one or more button-holes, a, which tab is attached to the re-enforced edge of the wrist-opening. The tab B is of such a 45 length that it extends to or beyond the wrist-stud of the sleeve. When not in use, the tab B may be folded back in opposite direction

and attached to a button, b, above the wrist-opening of the shirt, as shown in dotted lines in Fig. 3. In this position the tab is entirely 50 out of the way when it is not desired to be used. When the cuff is to be attached, the sleeve-buttons are first placed in the cuffs, and then plain studs, d, passed through the button-holes at the opposite side of the cuffs. The 55 button-hole of the tab B is then attached to the stud of the cuff, as shown in Fig. 1.

When it is desired to adjust the cuff on the sleeve so that it is supported higher or lower thereon, and extended more or less beyond the 60 sleeve of the coat, the tab B is provided with several button-holes, so that by folding the end of the tab and applying the folded tab to the rear stud, d, of the cuff the latter is set higher on the sleeve, as shown in Fig. 2. In this position a cheap and convenient cuff-holding 65 device is furnished, that forms a permanent part of the shirt, and by which cuffs can be quickly and conveniently attached to the sleeves and adjusted within certain limits on 70 the same.

Having thus described my invention, I claim as new and desire to secure by Letters Patent—

A shirt the sleeves of which are each provided with a placket having a re-enforce, and, 75 furthermore, provided with a tab attached to the outside of the sleeves above the wristband, the free ends of the tabs being adapted to lap over the said wristband, one or more button-holes being provided in the free end of the tab, 80 and a button being fastened at the upper end of the re-enforce of the placket-opening of the shirt-sleeve, said button serving for retaining the tab on the sleeve when said tab is not required for supporting the cuff, substantially 85 as set forth.

In testimony that I claim the foregoing as my invention I have signed my name in presence of two subscribing witnesses.

EMIL A. LEHMANN.
